UNITED STATES PATENT OFFICE.

LOUIS L. KORACH, OF CHICAGO, ILLINOIS.

RAIL ANCHOR OR ANTICREEPER.

1,265,093.

Specification of Letters Patent.

Patented May 7, 1918.

Application filed August 4, 1916. Serial No. 113,126.

To all whom it may concern:

Be it known that I, LOUIS L. KORACH, a citizen of the United States, residing in Chicago, in the county of Cook and State 5 of Illinois, have invented certain new and useful Improvements in Rail Anchors or Anticreepers, of which the following is a specification.

This invention relates to that class of rail 10 anchors which are adapted to be secured in engagement with a railway rail in position to engage a cross-tie or abutment, to prevent the creeping of the rail.

The principal object of the invention is 15 to provide a simple, economical, and efficient rail anchor or anticreeper for railway rails.

A further object of the invention is to provide a rail anchor or anticreeper having relatively movable clamping jaws adapted 20 to engage a railway rail, with simple and efficient means for securing the jaws firmly in clamping engagement with the rail, and adapted to enable the device to be mounted in position and removed with facility.

25 Other and further objects of the invention will appear from the following description and claims, and from an inspection of the accompanying drawings which are made a part hereof.

30 The invention consists in the features, combinations, parts, and details of construction herein described and claimed.

In the accompanying drawings Figure 1 is a plan view of a rail anchor or anti- 35 creeper constructed in accordance with my invention and improvements, showing the same secured in operative position upon a railway rail, and in engagement with a cross-tie.

40 Fig. 2, a view in transverse vertical section, taken on line 2 of Fig. 1, looking in the direction of the arrow.

Fig. 3, a view in side elevation, showing the device in engagement with a railway rail 45 and cross-tie, with a portion of the rail broken away.

Fig. 4, an enlarged plan view in detail of the pivoted or movable clamping jaw member shown in Fig. 1.

50 Fig. 5, an enlarged detail view in elevation of the clamping member shown in Fig. 4.

Fig. 6, a plan view in detail of the tie-engaging main jaw member, which extends 55 beneath the rail.

Fig. 7, a view in elevation of the main jaw member shown in Fig. 6.

Fig. 8, a view in side elevation of the main jaw and socket member shown in Fig. 7, as seen from the left of the figure. 60

Fig. 9, a perspective view in detail of a modified form of securing bolt or wedge.

In constructing a rail anchor or anticreeper in accordance with my invention and improvements, I provide a main jaw 65 and socket member 1, which comprises in its construction a base portion 2, which is adapted to extend beneath and in engagement with the bottom face of the base 3 of a railway rail 4, and having an upwardly 70 projecting rigid jaw portion 5, integral with the base and adapted to engage one edge of the rail base. The main jaw and socket member 1 is also provided with an upwardly projecting rigid jaw portion 6, at 75 the opposite extremity of said main jaw and socket member from that on which the jaw portion 5 is located. The jaw portion 5 has an inwardly extending approximately horizontal flange 7 at its upper extremity 80 which is adapted to extend inward over the adjacent longitudinal edge or margin 8 of the rail base and in engagement with the upper side of the rail base. The jaw portion 6, which is adapted to extend upward 85 on the opposite side of the rail from that on which the jaw portion 5 is located, is provided with an approximately horizontal inwardly projecting flange or jaw portion 9, which by preference extends inward above 90 the level of the top surface of the adjacent longitudinal margin or edge of the rail base, so as to provide a space between the rail base and said flange portion, and between the flange portion and the base 2. 95

The jaw 6, with its flange portion 9 extending inward and approximately horizontally over the base portion 2, is hollowed out so as to provide a socket 11, having a curved approximately semi-circular upright 100 wall portion 12 facing toward the central portion of the main jaw member 1 and toward the rail when the device is in operative position upon a rail. A movable jaw member 13, having a curved approximately 105 semi-circular end surface portion 14, corresponding with and adapted to bear against the curved wall portion 12 of the socket 11, and having a lower shouldered bar-engaging portion 15 which is adapted 110

to be inserted into position in the socket 11 through slot 16, is movably mounted in said socket 11, in engagement with a securing bar 22. This movable or pivoted jaw member 13 has a rail engaging end surface or jaw portion 17, which is adapted to engage the upright longitudinal edge or face of the rail when the curved end face 14 is seated in engagement with the curved socket wall 5 portion 12 above described, the portion of the jaw member 13 between the curved end 14 and the inner rail engaging end or jaw portion 17, being of such length that when the jaw member 13 is in position to 10 extend approximately at right angles with respect to the rail but in slightly oblique relation to the rail, the jaw will fit snugly in engagement with and between the engaged edge of the rail base and the socket 15 wall 12. (See Fig. 1.) It is plain that the movement of the rail engaging or inner movable end of the pivoted jaw member 13 from the position in which the latter is shown in full lines in Fig. 1, to the position 20 in which said jaw member is shown in broken lines in said figure, will tighten the engagement between the jaw member and the base of the rail, and cause the jaw member to bite into, or impinge against, 25 the rail base with increasing firmness and with an increasing degree of security corresponding with the extent of movement in the direction indicated, or in a direction tending to bring the pivoted jaw member 30 into locking position substantially at right angles with respect to the rail and in clutching engagement with the rail base. The movable or pivoted jaw member 13 is, by preference, provided with a slightly tapered 35 upper endwise projecting wedge portion or flange 18, which is adapted to be wedged firmly in position between the rigid flange 9 of the jaw 6 and the adjacent marginal portion of the rail base by the movement of the 40 jaw member 13 in the direction above indicated.

The main jaw member 1 is provided with a transverse aperture or slot 19, which extends transversely with respect to the rail 50 when the device is in operative position upon a rail. The upright wall portion 20 of this slot is, by preference, slightly oblique with respect to the upright wall portion 21 on the opposite side of the slot, and 55 a transverse securing bar or wedge 22 is inserted in the slot 19 in such position that the side face 23 is in slidable engagement with the adjacent face 24 of the pivoted jaw member 13 while the opposite side face 60 25 is in slidable engagement with the upright wall portion 21 of the slot 19, and the side face 23 of the wedge, near the end which is farthest from the pivoted jaw member is at the same time in slidable engagement with the wall portion 20 of the 65

slot. The portion of the slot between the oblique wall portion 27 and the wall 20 is made sufficiently wide to permit the bar or wedge member 22 to be driven into the slot and in engagement with the wall 20, the 70 pivoted jaw member 13 and the wall 21 and transversely with respect to the device and with respect to the longitudinal center of the rail, to force the pivoted jaw member 13 from the position in which it is shown in 75 full lines in Fig. 1 toward the position in which it is shown in broken lines in said figure, and into secure gripping engagement with the adjacent edge of the rail base. The transverse, but preferably oblique up- 80 right side wall 20 of the transverse slot 19 is thus at a slightly oblique angle with respect to the longitudinal center of the transverse locking bar or wedge member 22, when the latter is in position to engage said wall 85 20, the jaw portion 24 of the movable jaw 13 and the wall 21. From the foregoing it is plain that by driving or otherwise forcing the securing bar or wedge member 22 into the slot transversely with respect to the 90 device and with respect to the longitudinal center of the rail, from the position in which said bar or wedge member 22 is shown in full lines in Fig. 1, to the position in which it is shown in broken lines in said figure, 95 the pivoted or movable jaw member 13 will be forced into secure gripping or clutching engagement with the rail base, and that this result will be obtained whether the securing bar or wedge is of equal width 100 throughout its entire length, as shown in Fig. 1, or tapered as shown in Fig. 9. It is therefore practicable to use a metallic bar, which is of equal width throughout its entire length, and which is therefore of much 105 more economical construction than a tapered wedge or bar. It is obvious, however, that a tapered wedge, such as that shown in Fig. 9, may be used in lieu of the bar or wedge member 22 shown in Fig. 1, if desired, and 110 such a tapered wedge will operate in an efficient manner without materially changing the device in any substantial respect. The tapered wedge 28, as shown in Fig. 9, is adapted to be used in the slot 19 and in 115 lieu of the bar or wedge member 22, with the device constructed as above described and shown, although it is obvious that the wall 20 of the slot 19 is not required to be in oblique relation to the tapered wedge, but 120 may be parallel with the opposite wall 21 of the slot in case the tapered wedge is to be used.

The main jaw member 1 is provided with a transverse depending rib 29 which is 125 adapted to engage the adjacent upright side face of a cross-tie 30 when the device is in operative position upon a rail; and tapered flanges 31 are provided beneath the opposite side margins of the main jaw member 1, 130

which are adapted to strengthen and brace the main jaw member, and to cause any ice or frozen earth which may accumulate beneath or adjacent to the main jaw member 5 to be loosened, so as to prevent injury to the device or track when the rails expand or contract by reason of changes in temperature. In order that the device may have the maximum strength in proportion to the 10 weight of material used in its construction the base 2 is provided with strengthening ribs 32 and 33, which are adapted to engage the bottom face of the rail base.

I claim:

- 15 1. In a rail anchor, the combination of a main jaw member having opposite upwardly extending rigid jaw portions one of which is adapted to engage one side of a railway rail, a movable jaw member mounted in engagement with the other of said upwardly extending rigid jaw portions and with the opposite side of the rail, and a wedging member movable transversely with respect to the railway rail and located between and having its opposite sides in engagement with said jaw members and acting to press the movable jaw member in a direction lengthwise of the rail, to secure said jaw members in engagement with the rail.
- 20 2. In a rail anchor the combination of a main jaw member having a base portion adapted to extend beneath a railway rail, and having opposite upwardly extending rigid jaw portions one of which is adapted 25 to engage one side of the rail, a movable jaw member mounted in engagement with the other of said upwardly extending rigid jaw portions and adapted to engage the opposite side of the rail, and a wedging member 30 movable transversely with respect to the rail and located between and having its opposite sides in engagement with said jaw members, and adapted to tend to press the movable jaw member in a direction lengthwise of the rail.
- 35 3. In a rail anchor the combination of a main jaw member having a base portion adapted to extend beneath a railway rail, and having opposite upwardly extending rigid jaw portions one of which is adapted to engage one side of the rail, a movable jaw member mounted in engagement with the other of said upwardly extending rigid jaw portions and adapted to engage the opposite side of the rail, and a wedging member 40 movable transversely with respect to the rail and located between and having its opposite sides in engagement with said jaw members, and adapted to tend to press the movable jaw member in a direction length-

wise of the rail, to secure the jaw members 45 in engagement with the railway rail.

3. In a rail anchor, the combination of a main jaw member provided with a socket portion and having a rigid upwardly extending jaw portion adapted to engage one 50 side of a railway rail, a movable jaw member mounted in the socket portion of and in movable relation to said main jaw member and adapted to engage the opposite side of the rail, and a securing member movable 55 transversely with respect to the rail and located between and having its opposite sides in engagement with and in movable relation to said jaw members, and adapted to tend to press the movable jaw member in a direction lengthwise of the rail to secure the jaw members in engagement with the rail.

4. In a rail anchor, the combination of a main jaw member having a plurality of upwardly extending rigid jaw portions spaced 60 apart and adapted to admit a railway rail therebetween, one of which upwardly extending jaw portions is adapted to engage one side of the railway rail, a movable rail-engaging jaw member movably mounted in 65 engagement with the other one of said upwardly extending rigid jaw portions and adapted to extend between said last mentioned jaw portion and the adjacent side of the rail, and a wedging member movable 70 transversely with respect to the rail and located between and in engagement with and in movable relation to said movable jaw member and main jaw member, respectively, and acting to press the movable jaw member 75 in a direction lengthwise of the rail to secure said jaw members in engagement with a railway rail.

Signed at Chicago, Illinois, August 1, 1916.
